CLAIM

The ornamental design for a combined base station with mounting bracket, as shown and described.

DESCRIPTION

FIG. 1 is a front, right perspective view of a base station combined base station with mounting bracket showing my design therefor;

FIG. 2 is a rear, top perspective view thereof;

FIG. 3 is a side perspective view thereof;

FIG. 4 is a front, top perspective view thereof;

FIG. 5 is a side perspective view thereof;

FIG. 6 is a top perspective view thereof; and,

FIG. 7 is a bottom perspective view thereof.

The broken lines in the drawings depict portions of the combined base station with mounting bracket that form no part of the claim.
